JACKSON H. PRESSLEY, OF OCEANPORT, NEW JERSEY.

LONG-WAVE OR INTERMEDIATE-FREQUENCY TRANSFORMER.

Application filed October 18, 1924. Serial No. 744,376.

My invention relates to electric transformers and has for its object to provide a long wave or intermediate frequency transformer particularly adapted for use in radio receiving circuits, which object I accomplish as hereinafter described and as illustrated in the accompanying drawings. What I regard as new is set forth in the claims.

The disadvantages of and the difficulty 10 in building a transformer to operate at the incoming radio frequencies lie in the wide band of frequency which must be effectively covered. A transformer so designed must have such characteristics as to provide practically a constant ratio for all frequencies. To secure satisfactory operation when used in conjunction with an amplifier, the primary winding should have an impedance several times greater than filament to plate 15 resistance of the vacuum tube with which it is used. This impedance, largely reactive, is due to the inductance of the individual windings and the distributed capacity between transformer windings. Such conditions 20 promote resonance at certain critical frequencies resulting in good amplification at these points and rather poor amplification at others.

It has been common practice for radio engineers to design transformers which are to 30 operate at the incoming signal frequencies with the primary and secondary so adjusted with reference to the turns used and the leakage between primary and secondary, 35 that two resonant circuits,—one in the primary and the other in the secondary, are produced. These characteristics produce two resonant frequencies instead of one, with the result that reasonably good amplification 40 is secured over a considerable band of frequency.

In the super-heterodyne method of amplification, a local adjustable oscillator, or generator, is used to produce local oscillations 45 in the antenna circuit differing from the incoming signal frequency by another predetermined frequency. By proper adjustment of the local generator, this difference is kept the same for any signalling frequency. The 50 signalling frequency and the local impressed frequency interfere to form beats equal to the difference of the two frequencies. These oscillations are then rectified in the output circuit of the rectifier or detector tube. The 55 beat frequency appears as a true alternating current. This current is then amplified

by an amplifier whose transformers are designed to operate at this beat frequency which is made the same for any incoming frequency. The problem of transformer 60 design is therefore simplified and amplification is the same for all frequencies.

The difficulty of super-heterodyne transformer design is two-fold: first, to accomplish a design which will permit control 65 of regeneration; and second, to design a transformer which will operate without the necessity of a special regeneration control and that will function in this way for any type of tube now used in radio receiving 70 sets. I have discovered that these two requirements can be met by a transformer design in which there is negligible leakage between primary and secondary windings, and to this end I provide a transformer in 75 which the transformer coils are wound in bifilar fashion. Two approximately equal lengths of insulated copper wire are wound upon a spool side by side and at the same time, the ends of the wires constituting the 80 coils being attached to suitable terminals properly insulated. Such a transformer has approximately a one to one ratio, and corresponding turns of the primary and secondary are very closely adjacent to each 85 other, being separated by only the insulation of the wire. By winding the coils in this manner, the magnetic leakage is reduced to a minimum.

In the accompanying drawings, which 90 illustrate my improved transformer and the manner in which it is constructed,—

Fig. 1 is a perspective view of the complete transformer;

Fig. 2 is a horizontal section on line 2—2 95 of Fig. 1;

Fig. 3 is a vertical section on line 3—3 of Fig. 2;

Fig. 4 is a perspective view of one of the laminations of which the core is composed; 100

Fig. 5 is a perspective view illustrating the spool on which the coils are wound and the manner in which the winding is accomplished;

Fig. 6 is a perspective view of one of the 105 two similar members which together constitute the housing of the transformer; and

Fig. 7 is a curve or graph showing approximately the characteristics at various frequencies of my improved transformer. 110

My improved transformer comprises a magnetizable core 8 of the double loop type

composed of a plurality of thin steel laminations 9, preferably octagonal in contour, and each having a transverse centrally-disposed tongue 10, on the opposite sides of which are 5 openings 11, 12, thus giving the double loop formation above mentioned. The tongues 10 of the several laminations, when superposed in the manner illustrated in Fig. 2, together form a central core 13 upon which is mounted 10 a spool 14 lying in the openings 11, 12, as shown in Fig. 3. Wound upon the spool 14 in bifilar fashion are two fine insulated copper wires 15, 16 respectively constituting the primary and secondary coils of the transformer. These wires are of approximately 15 equal length, and are wound upon the spool side by side and at the same time, so that adjacent sections of the windings occupy approximately the same position on the spool, and corresponding turns of the primary and 20 secondary coils are very closely adjacent to each other, being separated only by the insulation of the wire. As shown in Fig. 5, the spool 14 is provided with a rectangular central opening or bore 17 to adapt it to fit nicely on the central core 10, and at diametrically opposite sides of said opening it is provided with grooves or recesses 18, 19 to receive terminal wires 20, 21 that are connected with 25 the inner ends of the coil wires 15, 16. When the coils have received the required number of turns suitable terminal wires are attached to the outer ends of the coil wires 15, 16, and the several terminal wires are connected to 30 binding posts, as will be hereinafter described. By winding the coils in bifilar fashion as described magnetic leakage is reduced to a minimum.

After the coils have been formed as above 35 described, the spool is mounted upon the central core 10 by threading a sufficient number of laminations 9 into the opening 17 of the spool, after which the core composed of the several laminations is formed into a unitary mass by clamping the laminations together 40 in a housing composed of two complementary members 22, 23 made of insulating material. These members are rectangular in contour, and are provided with triangular corner lugs 24 at their inner faces so that 45 they fit snugly upon the core, as illustrated in Fig. 1. Screws 25 extending through the corner portions of the housing members 22, 23 serve to clamp them together so that they 50 enclose the core at the sides and at the corners. The housing members 22, 23 are also provided with semi-cylindrical portions 26 which extend over and enclose the projecting portions of the spool 14 so that the spool is 55 entirely enclosed and protected. At one side of each of the semi-cylindrical portions 26 holes 27, 28 are provided for the passage of the terminal wires of the coils, as illustrated in Fig. 1. Binding posts 29, 30 are provided 60 on the housing member 22, and similar bind- 65 ing posts 31, 32 are provided on the other housing member 23, and to one of these pairs of binding posts the terminal wires of the primary coil are connected, while to the other pair the terminal wires of the secondary coil 70 are connected. In the illustrated arrangement one of the primary terminals 20 is shown as connected to the binding post 29, and the other primary terminal 33 is shown connected to the binding post 30. In like 75 manner the secondary terminal wire 21 will be connected to the binding post 31 and the other secondary terminal 34 will be connected with binding post 32. The disposition of the several binding posts is, of course, optional, as they may be arranged wherever is most convenient, as for example, if the transformer is designed to stand on end the binding posts may be placed at the upper end instead of at the upper side of the housing. 80 The several binding posts are preferably made of metal but are suitably insulated.

The advantages of my improved transformer are two-fold: First, the ratio as a function of the applied radio frequencies 85 is more nearly constant than is possible with any other type of winding. This characteristic is illustrated in Fig. 5. Second, when used in radio frequency receiving sets designed to operate within the range of frequencies indicated, there is less tendency toward regeneration and stability of operation is greatly increased.

What I claim as my invention and desire to secure by Letters Patent, is—

1. In an intermediate frequency transformer for superheterodyne receiving sets, the combination of a magnetizable core composed of a plurality of laminations octagonal in outline, each lamination having a centrally disposed member having a free end capable of being sprung outwardly from the lamination, a spool having a central opening of rectangular form, the centrally disposed members of said core laminations being threaded through the opening in said spool, primary and secondary windings both wound simultaneously on said spool in bifilar relation, the rectangular opening in said spool having slots therein through which the inner ends of said windings are extended to the outside of said spool, two housing sections each comprising a flange portion having laterally projecting lugs adapted to engage over the sloping corners of said core, and having a semi-cylindrical portion projecting from said flange portion for receiving the outer side of said spool, screw means passing through said lugs for securing said housing sections over said core and spool, said core having edge portions exposed through openings intervening between said lugs, and binding posts projecting laterally from each flange portion, the terminal ends of said windings extending 10

up through holes in said semi-cylindrical portions and connecting to said binding posts.

2. In an intermediate frequency transformer for superheterodyne receivers, the combination of a magnetizable core, composed of a plurality of laminations of double loop form, each lamination having a centrally disposed member, one end of which is free, a spool having a central opening through which the free ends of said centrally disposed members are threaded, primary and secondary windings both wound simultaneously on said spool in bifilar relation, a housing comprising two complementary housing sections each comprising a flange portion having laterally projecting lugs adapted to engage over the edges of said core and having semi-cylindrical portions projecting from said flange portions for receiving the sides of said spools, screw means passing through said laterally pro-

jecting lugs for securing said housing sections together, and binding posts mounted on said housing sections and connected to 25 said primary and secondary windings.

3. An electric transformer comprising a magnetizable core composed of a plurality of laminations shaped to provide a centrally disposed member, a spool mounted on said member, primary and secondary windings on said spool, and a housing for enclosing said core and spool comprising two complementary housing sections, each having a flange portion provided with laterally extending lugs adapted to engage over the edges of said core and having a semi-cylindrical portion adapted to engage over the outer side of said spool, screw means passing through said lugs for securing said housing sections together, and connector terminals mounted on the flange portions of said housing sections. 30 35 40
